Germany, assignor to Fried. Krupp, Gruson-
werk, Aktien-Gesellschaft, Magdeburg-Buckau,
Germany

Application September 27, 1937, Serial No. 165,859
In Germany October 1, 1936

3 Claims. (CL 209—3)

Our invention relates to gyrating scrubbers for washing and scrubbing ores, sand, gravel and other materials in bulk with the object of removing fines therefrom and positively separating 5 impurities and foreign matter such as clay, tone, lime and like adhesives, which are crusted and dried thereon and often tenaciously stick to the lumps and granules of the material concerned.

The principal object of the invention is to 10 provide a structurally improved gyrating scrubber for the purpose set forth which is highly simple and inexpensive in its construction, reliable in operation and requiring relatively little power and expenditure for maintenance and re- 15 pair.

In connection therewith the invention aims at providing a gyrating scrubber having a relatively high efficiency and great output per hour considering the floor space and power required yet 20 so designed, that the liability of breaking up and comminuting the material under treatment is reduced to a minimum.

Briefly stated the invention consists in cooperatively associating a plurality of scrubbing 25 troughs of special design having one-dimensionally curved inner working faces and being substantially horizontally arranged side by side with their crests substantially in a level straight line, and in bodily gyrating said troughs in substantially vertically disposed cycles of movement perpendicular to their crests and in clockwise direction of rotation as indicated by arrow *i* in Fig. 1 of the drawing.

The inventors have found that by so designing, arranging and gyrating said troughs the material fed thereto will spontaneously climb over 35 their crests and will be positively advanced through the troughs viz. dynamically—as against statically or gravitationally.

The inventors attribute the spontaneous migration of the material through the troughs to the fact that the agglomerates, lumps and granules of which the material is composed receive by virtue of their frictional engagement with 40 the gyrating inner walls of the troughs violent rotary impacts in quick succession and in a specific sense or direction, namely with the result, that they are thrown off the gyrating surface and are incidentally rolled around in anticlockwise direction as indicated by arrow *x* in Fig. 2 45 of the drawing, and that in turn the whole mass of the material performing a rolling and trundling motion is displaced, namely lifted—as on the ascending inner walls of a rotary ball mill.

50 Another salient feature of the invention is

the provision of a relatively thick lining of resilient material in the scrubber, capable of being replaced at low cost, with the object of enhancing the frictional interengagement of the inner working faces of the scrubber and the material under 5 treatment, thereby promoting the migration and agitation of the material in the troughs, safeguarding the latter against excessive wear and intensifying the scrubbing effect.

Still other objects of the invention will be 10 come incidentally apparent to practitioners in this field as the specification proceeds.

The nature and scope of this invention are briefly outlined in the appended claims and will be more fully understood from the following 15 specification taken together with the drawing, in which

Fig. 1 is a perspective view diagrammatically showing by way of an example a gyrating scrubber designed according to this invention; 20

Fig. 2 is a cross section longitudinally taken through the trough section of a structurally modified scrubbing machine designed according to this invention;

Fig. 3 is another fragmentary cross section in 25 a larger scale showing a guide plate as provided in the troughs of the scrubber according to this invention;

Fig. 4 is a fragmentary section showing a 30 trough of modified cross sectional shape;

Figs. 5-7 are cross sectional views showing 35 baffle members and their adjusting means as provided according to this invention for controlling the travel of the material through the scrubbing machine;

Figs. 8 and 9 are cross sections drawn in different scales through one of the troughs of the scrubber having a perforated bottom and being lined with india rubber or the like.

The gyrating scrubber shown in Figs. 1 and 2 40 and designed with the objects in view outlined above, comprises:

(1) A support representing the machine bed 11;

(2) An open box frame 12, resiliently mounted 45 at its four corners on said support by means of coil springs 13, 13' and brackets 14, 14', so as to be capable of being bodily gyrated in vertically disposed paths of movement and in clockwise direction indicated by arrow *i*;

(3) Means for gyrating said frame, which comprise an eccentric shaft 20, crosswisely extending through the frame 12 in engagement therewith and being carried at both its ends in bearings 21, which are fixed on the support 11; 50 55

levers 22, on which balance weights 23 are adjustably fixed and which are fixed near both ends of the eccentric shaft 20 for counterbalancing the centrifugal forces produced while the machine is in action; a pulley 26 for rotating the eccentric shaft 20, and a prime mover (not shown);

(4) A plurality of trough shaped material receiving elements having one-dimensionally curved inner working or "impeller" faces, which are mounted in frame 12, being fixed on the side walls of the latter with their axes in substantially parallel relation to the shaft; in the embodiment of the invention shown in Fig. 1 all the troughs 3b, 3c, 3d, 3e are perforated except the trough 3a at the feed end of the scrubbing machine, where feeding means of conventional design are provided symbolically, indicated by an arrow a, while in Fig. 2 all the troughs 3f, 3g, 3h, 3i, 3k are perforated;

(5) A system of sprinkler pipes 40, which is mounted above the washing troughs and to which water is supplied through main pipe 41.

On gyrating the scrubbing machine described in clockwise direction by rotating the eccentric shaft 20 the material, which is fed into the machine at a, is given a trundling motion and while rolling around in circular and elliptic paths of movement interlooping each other as indicated by loops and arrows x, namely in anticlockwise direction, will be dynamically advanced—as against gravitationally—and pass directly from trough to trough over their upper edge or crest portions r; the material being exposed to the jets of water during its travel through the machine is thoroughly washed and is discharged over the chutes 48, 48'.

In cases, where the material to be scrubbed is mixed with impurities and adhesives firmly dried and tenaciously sticking thereon, one or more washing troughs, which are not perforated may be provided according to this invention at the feed end of the machine as shown at 3a in Fig. 1, wherein the material is first thoroughly soaked in water with the object of conditioning, namely mollifying and softening the adhesives concerned for the subsequent treatment in the scrubbing troughs proper 3b, 3c, 3d, 3e.

As seen in Fig. 3 guide plates 50 of curved cross sectional shape substantially corresponding to that of the bottom of the troughs and extending longitudinally therethrough may be provided with the object of guiding the material in close proximity and positive engagement with the gyrating trough surface so as to promote the trundling motion imparted to the material and enhance the scrubbing action.

As seen in Figs. 5 to 7 troughs 3n of a modified cross section shape having their less steeply inclined working face n' at the delivery end may be used to advantage, namely in connection with baffle members in the form of flat bars 60 adjustably fixed on the side walls of the frame 12.

In the embodiment of the invention shown by way of an example the means for adjusting said baffle members 60 in vertical and horizontal direction relatively to the working face n' and crests r of the troughs comprise angle irons 61, 61' having vertical slots, wherein the baffle members 60 are slidably fixed by clamping screws 62, and horizontal slots formed in the frame 12, wherein said angle irons 61, 61' are slidably fixed by clamping screws 63, 63', 64, 64'.

In the course of their experimental work the inventors have found that the scrubbing action

upon the material under treatment is greatly intensified, that the expenditure for maintenance and repair of gyrating scrubbers can be appreciably reduced, and that their life can be considerably lengthened by lining the working faces of the washing and scrubbing troughs with a relatively thick coating of rubber, indicated at 70 in Figs. 8 and 9, or kindred relatively soft resilient material impervious to water preferably artificial German rubber known as "Buna" as now produced on a large scale and in qualities superior to genuine India rubber, namely as regards resistance to wear and anti-ageing properties.

Good results have been obtained with rubber linings 10 to 12 mm. thick.

The rubber lining may be given to advantage a roughened or corrugated surface as indicated at 71 in Fig. 9: by said roughened and relatively thick rubber lining the trundling motion imparted to the material under treatment by the gyrating troughs and consequently the scrubbing effect is greatly intensified; also the inner surfaces and lower edges of the holes in the scrubbing troughs should be lined with rubber or a like protective coating as shown at 72 in Figs. 8 and 9 in order to prevent premature wear and excessive widening of the holes.

Various other modifications and changes may be conveniently made in the structural details of gyrating scrubbers of the improved design described without departing from the spirit and the salient ideas of this invention:

For instance instead of troughs having a somewhat parabolic or hyperbolic cross sectional shape shown in Figs. 1 to 3, 5 and 9 semicircularly shaped troughs 30, as shown in Fig. 4 may be used to advantage under specific working conditions.

What we claim is:

1. A machine for continuously scrubbing material in bulk, which comprises a plurality of scrubbing troughs having one-dimensionally curved inner working faces and being adjacently to each other arranged side by side for communication at their crests, the latter being substantially in the same level plane, of side walls closing the ends of said troughs and extending above their crests, means at the front end of the machine for feeding the material thereinto, means for gyrating said troughs in closed cycles of movement substantially perpendicular to their crests, means at the rear end of the machine for discharging the material therefrom, and baffle members in the form of flat bars provided at the said crests for controlling the passage of the material thereover.

2. A machine for continuously scrubbing material in bulk, which comprises a plurality of scrubbing troughs having one-dimensionally curved inner working faces and being adjacently to each other arranged side by side for communication at their crests, the latter being substantially in the same level plane, of side walls closing the ends of said troughs and extending above their crests, means at the front end of the machine for feeding the material thereinto, means for gyrating said troughs in closed cycles of movement substantially perpendicular to their crests, means at the rear end of the machine for discharging the material therefrom, baffle members in the form of flat bars provided at said crest portions for controlling the passage of the material thereover, and means for adjusting the position of said baffle members in vertical and horizontal direction.

3. A machine for continuously scrubbing material in bulk, which comprises a plurality of scrubbing troughs having one-dimensionally curved inner working faces and being adjacently 5 to each other arranged side by side for communication at their crests, the latter being substantially in the same level plane, of side walls closing the ends of said troughs and extending above crests, means at the front end of the machine for 10 feeding the material thereto, means for gyrat-

ing said troughs in closed cycles of movement substantially perpendicular to their crests, means at the rear end of the machine for discharging the material therefrom, and material guiding members in the form of bars of curved cross section shape provided in said troughs, their shapes being conform to that of the opposed working faces of the troughs. 5

GERHARD LINKE.
AUGUST VOESEL. 10
